UNITED STATES PATENT OFFICE.

GEORGE SCHAUB, OF HAMBURG.

IMPROVEMENT IN CASTING TYPES FOR PRINTING.

Specification forming part of Letters Patent No. 19,797, dated March 30, 1852.

To all whom it may concern:

Be it known that I, GEORGE SCHAUB, a citizen of the free town of Hamburg, but at present residing at Birmingham, in the county of Warwick, England, electro-metallurgist, have invented or discovered a new or Improved Manufacture of Types for Printing and Spaces used in Setting up Printing-Types; and I, the said GEORGE SCHAUB, do hereby declare the nature of the said invention, and in what manner the same is to be performed, to be particularly described and ascertained in and by the following statement thereof, that is to say—

My said invention consists in manufacturing types for printing, the heads or printing-surfaces of which said types are made, as herein-after explained, and illustrated by the drawing, of copper or alloy of copper, zinc or alloy of zinc, nickel or alloy of nickel, or such other metal or alloy as is or may be suitable for the production of the said type-heads or printing-surfaces; also, of the manufacture of spaces used in setting up types, as herein explained. The said heads or printing-surfaces of the types are made either by the process of electro-deposition or by mechanical means. When the said heads are made by electro-deposition, I effect the deposition of copper or other suitable metal or alloy in molds constructed in the manner illustrated in the accompanying drawings.

I take a series of bars of metal of the form represented in plan at *a*, Figure 1, the said bars being plain on one side and serrated on the other, as represented. I prefer to join two of the bars *a* together, back to back, so as to form a compound bar of the shape represented at *b*. When the serrated faces of the bars *a b* are presented to each other, spaces of the form represented at *c*, Fig. 2, are left between the said bars, and in the said spaces *c c* types of the ordinary kind are dropped, the heads of the said types projecting above the tops of the plates in which the holes *c c* are formed. A frame, *e*, is provided with a series of the compound bars *b b*, which said bars are fixed in the said frame *e* by two screws, *ff*. The said frame *e* is dropped into a shallow box, *g*.

Fig. 3 represents in longitudinal section the box *g*, containing the frame *e*, with the com-

pound bars *b b*. The summits or heads of the types are marked *d d* in Fig. 3.

Fig. 4 represents a transverse section of Fig. 2. A cast is taken of the heads of the types *d d* by plaster-of-paris, gutta-percha, or otherwise; or I take an impression from the said types by the well-known electrotype process. I then deposit copper or other metal or alloy in the cast or mold obtained, as described, and thus procure a sheet of metal consisting of the heads of types arranged in a series side by side, and having depressed divisions between them, so that they can afterward be readily divided. I attach or run soft solder on the back of the sheet of type-heads, and by filing or otherwise reduce the thickness of the sheet, so that the parts between the type-heads shall be very thin. I place the said sheet of type-heads on the bottom of the box *g*, the soldered back of the sheet of type-heads being uppermost. I then place upon the sheet of type-heads the frame *e*, (filled with the bars *b b*, the spaces *c c* being unoccupied.) I then fill the box *g* with molten type-metal, which runs down and fills the spaces *c c*, the said type-metal attaching itself to the soldered plate, which closes the bottoms of the spaces *c c*. There is thus produced a series of type-bodies soldered at one end to the sheet of type-heads, each of the type-bodies being immediately at the back of one of the type-heads. The superfluous metal is poured from the box *g*, and when the molds or bars *b b* have sufficiently cooled and the metal in the spaces *c c* has solidified the screws *ff* are withdrawn and the bars *b b* liberated. On the removal of the plates or bars *b b* the sheet of type-heads having type-bodies soldered at their backs is divided by sawing or breaking off. The broken edges of the type-heads are rendered smooth by grinding or otherwise. The bottom of the type is shaped, and the guide in the side thereof produced by filing or otherwise.

When I produce a sheet of type-heads by mechanical means, I emboss or raise the same by dies and pressure, according to the well-known processes of raising metals. I afterward attach the type-bodies to the backs of the type-heads, and finish the types in the manner already described with reference to Figs. 1, 2, 3, and 4.

I sometimes dispense with the box *g*, making the frame *e* of greater height than is represented in the drawings, so as to enable it to hold a depth of liquid metal equal to that held by the box *g*. I close the bottom of the frame *e* by a plate of metal or by a plaster or electro-type cast, in which the sheet of type-heads fits.

My method of casting type-bodies is applicable to the casting of the pieces used in letter-press printing, called "spaces," "quadrats," and otherwise, which spaces and quadrats are used, as is well known, between the letters, words, or lines in printing. I cast the said spaces and quadrats by the use of the plates *b b*, the spaces *cc* being made of the requisite size and form. The bottom of the frame *e* is closed with a plain surface.

I sometimes effect the various kinds of casting herein described under pressure.

I will describe the method I pursue with reference to Figs. 2 and 3. The top of the box *g* is closed by a plate, or the said plate rests upon the top of the frame *e*. A funnel of any desired height is fixed in a hole in the said plate, and the molten metal is poured down the said funnel and made to fill the spaces *cc* and the funnel. The pressure of the molten metal in the said funnel makes the casting more dense and sound. When the plate rests upon the top of the frame *e*, a channel is made from the funnel on the under surface of the

said plate communicating with a series of branch channels running over each row of the spaces *cc*. The said channels conduct the metal from the funnel to the several spaces in which the casting is effected.

Having now described the nature of my said invention and the manner of carrying the same into effect, I wish it to be understood that I do not limit myself to the precise details herein described and represented, as the same may be varied without departing from the nature of my said invention; but

I claim as my invention—

The new or improved manufacture of types for printing, hereinbefore described, and illustrated by the accompanying drawing—that is to say, manufacturing types for printing by casting the stems or bodies of the types at the back of a sheet of type-heads and finishing the same, as described, also the manufacture of spaces used in setting up printing-types by the use of the movable frame herein described and represented.

In testimony whereof I have signed my name to this specification before two subscribing witnesses.

GEORGE SCHAUB.

Witnesses:

GEORGE SHAW,
RICHARD SKERRETT.
